UNITED STATES PATENT OFFICE.

HENRY PRICE BALL, OF BROOKLYN, NEW YORK, ASSIGNOR TO S. STERNAU & CO., INC., OF NEW YORK, N. Y., A CORPORATION OF NEW YORK.

GRID OR GRILL.

1,373,788.

Specification of Letters Patent.

Patented Apr. 5, 1921.

Application filed September 15, 1920. Serial No. 410,441.

To all whom it may concern:

Be it known that I, HENRY PRICE BALL, a citizen of the United States, and a resident of the borough of Brooklyn, county of 5 Kings, city and State of New York, have invented a certain new and useful Grid or Grill, of which the following is a specification.

The invention relates to devices on which 10 steaks, chops or the like may be broiled or grilled, and more particularly to such a device which may be employed in connection with a heating device employing alcohol as a fuel, such as is illustrated and described in 15 the copending application for patent executed on even date herewith; but it is to be understood that the device of the invention may, in whole or in parts, be employed in connection with other forms of fuel and 20 with or without the use of a stove or lamp.

The objects of the invention are to provide a device of the character described in which the heat will be evenly distributed over the surface; which may be in sections 25 thereby promoting portability, the surface of which may be extended; in which leakage between the sections will be prevented; which will be cheap to construct and install; in which the greases and juices produced 30 by cooking may be collected and saved; and which will not get out of order.

These and further objects will more fully appear in the following specification and accompanying drawings considered together 35 or separately.

The invention is designed primarily for dining and buffet cars, but it is to be understood that it may be employed in other situations.

40 One embodiment of the invention is illustrated in the accompanying drawings in which like parts in all of the several figures are designated by similar characters of reference, and in which—

45 Figure 1 is a top plan view of the grid or grill constructed in accordance with the invention.

Fig. 2 is a section on the line 2—2 of Fig. 1.

50 Fig. 3 is a section on the line 3—3 of Fig. 1.

Fig. 4 is a bottom plan view of a grid or grill section, and

55 Fig. 5 is a section on the line 5—5 of Fig. 4.

In the embodiment of the invention illustrated 1 designates a hearth which may be composed of brick, tiling or the like; and 2 the side walls of the cooking compartment which may be of similar material. Arranged on each side wall is a series of rails 3 on which is supported as by means of rollers 4, a frame 5 in which rests a pair of grill members 6 and 7.

Each grill member comprises a front rail 8 and a back rail 9. The height of the back rail 9 is greater than that of the front rail 8. The rails are connected by a plate 10 formed of parallel plications extending from the back rail 9 to a point within a short distance from the front rail 8. That portion of the plate 10 between the front ends of the plications and the front rail lies below the level of the plications to form a trough 12 between the plicated portion of the plate and the front rail.

The tops of the plications of the plate are on the levels of the tops of the rails 8 and 9, and consequently the plate 10 is higher at the back than at the front and the grooves formed by the plications will drain to the front and into the trough 12. The bottom of the trough 12 is higher at one end than at the other and the lower end of the trough is provided with a drain opening 13, as shown, whereby fluids drained from the plate 10 will be discharged at one corner of the grill into a cup or other receptacle placed beneath the opening 13, and may be saved.

90 The frame 5 comprises end members, by which the rollers 4 are carried, and a front member 14 and a back member 15. The front and back members are provided with flanges on which the rails 8 and 9 rest whereby the grill member is supported in the frame.

95 The grill member is preferably composed of cast iron and the plications appear on both sides thereof whereby a light and easily handled structure will be produced. At one side of the member the plication is incomplete and that end of the member presents an upturned ledge 16. At the opposite end of the member the last plication is also incomplete but presents a downturned ledge 17. The latter ledge may, and preferably does, engage over the end member of the frame 5 as shown.

100 Preferably the grill members are used in

pairs with the ledge 16 of one overlapping the ledge 15 of the other, whereby a covered joint between the members is produced and leakage between them prevented. When 5 the grill members are used in pairs the troughs 12 incline in opposite directions from the joint between the members, and the drain openings 13 will be at opposite sides of the hearth and in proximity to the side 10 walls 2 of the compartment, and the drip cups will not interfere with stoves or other heating medium carried on the hearth and beneath the grill members.

In order to provide for a more equalized 15 distribution of heat over the surface of the grill, the valleys on the underside of the grill are obliterated in part, at least whereby the plate is thickened, as at 18, and the increased mass of metal in the thickened portion 20 or portions and the greater conductivity of heat by such portion, together with the relatively small radiating surface of the thickened portions, will more evenly distribute the heat, and to a greater distance 25 from the directly heated portion, than will the relatively thin metal of the major portion of the plate. The greater conductivity of the portions 18 will also prevent the plate from becoming unduly heated at the point 30 or points directly over the source, or sources, of heat, and will prevent warping of the plate.

In the embodiment of the invention illustrated in which the stove or burner above 35 mentioned is preferably employed as the heating medium, four thickened zones are shown, each comprising a circular portion beneath which a fuel receptacle is positioned, as shown in broken lines in Fig. 1, and with 40 a tail radiating to a corner of the grill. It is to be understood that as many portions 18 as there are sources of heat used may be employed, or a single thickened portion having a plurality of radiating tails may be used.

45 In accordance with the provisions of the patent statutes the principle of the invention, together with what is now considered to be the best embodiment thereof, have been described, but it is to be understood 50 that the apparatus described is merely illustrative, and that the invention may be carried out in other ways.

The invention having been described what 55 is claimed and desired to be secured by Letters Patent is:—

1. A device of the character described, comprising a relatively thin plate adapted to be positioned above the flame of a source of heat, that portion of the plate directly 60 above the flame being of relatively small area as compared to the area of the plate, there being a portion of the plate thicker than the major portion thereof, said thickened portion adapted to be in vertical alignment with the source of heat.

2. A device of the character described, comprising a relatively thin plate adapted to be positioned above the flame of a source of heat, that portion of the plate directly 70 above the flame being of relatively small area as compared to the area of the plate, there being a portion of the plate thicker than the major portion thereof, said thickened portion adapted to be in vertical alignment with the source of heat, and having a portion thereof extending to a distance 75 therefrom.

3. A device of the character described, comprising a plicated plate, there being portions of the valleys on the under side of 80 the plate obliterated to form zones of greater thickness than the body of the plate.

4. A device of the character described, comprising a plicated plate, there being portions of the valleys on the under side of the 85 plate obliterated to form zones of greater thickness than the body of the plate, said thickened portions being of comet-like form.

5. A device of the character described, comprising a plicated plate, there being portions of the valleys on the under side of the plate obliterated to form zones of greater 90 thickness than the body of the plate, said thickened portions being of comet-like form, with the tail thereof extending toward the 95 edge of the plate.

6. A device of the character described, comprising a plicated plate, the plications extending to opposite extremities of the plate the outer plications being incomplete, 100 that at one side of having a downturned edge, the opposite plication having an upturned edge.

7. A device of the character described, comprising a plicated plate, supports for 105 the plates, said supports extending across opposite ends of the plate and at right angles to plications thereof, one support being higher than the other whereby the plate will be pitched to drain toward one end thereof, 110 there being a trough between the plications and the lower support and extending at right angles to the plications, said trough being lower at one end than at the other and having a drain opening at the lower end. 115

8. A device of the character described, comprising a plurality of plicated plates arranged side-by-side with the plications arranged side-by-side and parallel, the plication at one side of one plate having a 120 downturned edge, the plication at one side of the adjoining plate having an upturned edge, the said downturned edge overlapping the upturned edge of the adjoining plate, and a frame for supporting the plate. 125

9. A device of the character described, comprising a plurality of plicated plates arranged side-by-side with the plications arranged side-by-side and parallel, the plication at one side of each plate having a 130

downturned edge, the plication of the opposite side of each plate having an upturned edge, the said downturned edge of one plate overlapping the upturned edge of the adjoining plate, and a frame for supporting the plates.

10. A device of the character described, comprising a plurality of plicated plates arranged side-by-side with the plications arranged side-by-side and parallel, the plications at one side of each plate having a downturned edge, the plication at the opposite side of each plate having an upturned edge, the said downturned edge of one plate

overlapping the upturned edge of the adjoining plate, there being a trough at one end of each plate, said troughs being in alinement, the troughs of each pair of plates pitching in opposite directions, there being a drain opening in the lower portion of each trough, and a frame for supporting the plates.

This specification signed and witnessed this 8th day of September, 1920.

HENRY PRICE BALL.
